Primary Examiner — Paula Allen Greene(57) **CLAIM**

The ornamental design for a portion of cat headphone, as shown and described.

DESCRIPTION

FIG. 1 is a front and top perspective view of a portion of cat headphone design showing my new design.

FIG. 2 is a front view of a portion of cat headphone.

FIG. 3 is a rear view of a portion of cat headphone.

FIG. 4 is a left side view of a portion of cat headphone.

FIG. 5 is a right side view of a portion of cat headphone.

FIG. 6 is a top view of a portion of cat headphone; and,

FIG. 7 is a bottom view of a portion of cat headphone.

The dashed broken lines on the portion of the cat headphone represent stitching; all the dashed broken lines form no part of the claimed design.
